UNITED STATES PATENT OFFICE

2,327,630

COOLER CABINET

Murray M. Fibus, Youngstown, Ohio

Application January 7, 1942, Serial No. 425,881

1 Claim. (Cl. 220—14)

This invention relates to a cooler cabinet and more particularly to a cabinet adapted to be used as an essential portion of a beverage cooler.

The principal object of the invention is the provision of a cabinet so designed that the structural form thereof serves the dual purposes of enclosing other essential portions of the beverage cooler in an insulated manner and cooperates with other portions of beverage coolers particularly resilient gaskets in effecting the tight closure about each of a plurality of orifices therein.

A further object of the invention is the provision of a cabinet provided with removable top portions so formed as to cause the distortion of resilient gaskets used in connection with orifices formed therein.

A still further object of the invention is the provision of a cabinet the top portions of which are provided with means for engaging the inner-most edges of the vertical wall sections of the same in order to insure the positive positioning of the top sections with respect to the vertical wall sections and said respect to a plurality of beverage receiving chambers positioned therein and about which a plurality of resilient gaskets are provided.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a top plan view of a cooler cabinet.

Figure 2 is a side elevation of one of the top sections of the cabinet illustrated in Figure 1.

Figure 3 is a side elevation of the cooler cabinet taken on line 3—3 of Figure 1 and shows in cross-sectional detail the formation thereof.

Figure 4 is an enlarged cross-sectional side elevation of one of a plurality of resilient gaskets employed in the cooler cabinet. Dotted lines in Figure 4 illustrates the relative positions of the top sections of the cooler cabinet as well as one of the beverage chambers.

By referring to the drawing and Figures 1, 2, and 3 in particular, it will be seen that the cabinet comprises a rectangular box-like structure preferably formed of sheet metal and which structure is generally indicated by the numeral 10. The front and back sections, side sections, and the bottom section being formed in a singular

unit and the top being provided in the form of two sections with an axially extending joint therebetween. The top sections are indicated by the numerals 11 and 12, respectively, and it will be noted that each of these sections have a plurality of half-circular openings 13 and 14, respectively, formed therein which when brought together in closed relationship as illustrated in Figure 1 form a complete circle.

By referring to Figure 2, it will be seen that each of these top sections 11 and 12 are provided with oppositely disposed downturned flanges 15 and 16, respectively, which flanges are also shown in dotted lines in Figure 1 and which flanges are adapted to engage the inner-most edges of the vertical front and back walls of the cabinet structure. The downturned flanges 15 and 16 serve to cause the top portions 11 and 12, respectively, to be brought together forcibly and to, due to their formation, effect the distortion of any object such as resilient gaskets positioned in each of the openings formed by the half-circular sections 13 and 14 and consequently about the neck of a chamber 17 a plurality of which are adapted to be positioned within the cabinet and the upper-most edges of which are adapted to terminate short of the upper-most surfaces of the top portions 11 and 12.

By referring to Figure 3 in particular, it will be seen that a resilient gasket of the type referred to is indicated by the numeral 18 and is shown in position over the neck portion of a beverage chamber 17 which beverage chamber 17 preferably comprises a crock which, it will be obvious, will provide for the adequate cooling of any beverage therein when the same is surrounded on its exterior surfaces with ice-water or water in which refrigeration coils are positioned. It will be seen that the half-circular openings 13 and 14 of the top sections 11 and 12, respectively, fit tightly against the exterior rim of the gasket 18 and causes the same to be slightly distorted and thus positively fill all of the available space between the neck of the chamber 17 and the circular areas of the top portions 11 and 12. This is caused as has heretofore been stated by the forceful positioning of the top portions 11 and 12 which as will be remembered are unable to move outwardly due to the presence of the downwardly depending flanges 15 and 16 along the front and back edges of the top portions. Thus the dual utility is achieved in that the resulting distortion of the resilient gasket, preferably rubber, insures the positive retention of the top portions 11 and 12 in proper position and at the

same time holds the gaskets 18 firmly upon the neck of the jug and at the same time closes the air space otherwise existing thereabout. When the top portions 11 and 12 have thus been placed about the chambers 17 and the resilient gaskets 18 thus firmly positioned in the same, it will be seen that the device is then ready to receive inverted jugs or bottles of almost any size and containing any beverage.

In Figure 3 it will be observed that a plurality of spigots 19 are positioned upon the front of the cooling cabinet which spigots communicate, one with each of the beverage chambers thereby making it possible to draw off the contents of the containers of the chambers at will. It is obvious that the exterior design of these cabinets may be varied and is preferably attractive in general over all appearance such as, for example, is shown in my design patent, D-132,894, issued June 30, 1942.

By referring to Figure 4, a cross-sectional detail view of one of the resilient gaskets necessarily employed is illustrated it being noted that the gasket is indicated by the numeral 18 and that dotted lines illustrate the relative positions of the top portions 11 and 12 and the beverage chamber 17. It will be seen that the gasket is formed with a wide annular inturned and depending flange 20 which flange terminates about a centrally positioned opening 21 through which the neck of the bottle, jug, or other article is positioned when introducing beverages into the chamber 17. It will be observed that the formation of the gasket 18 includes relatively thicker downturned annular flange portions 22 which functioning between the top portions 11 and 12 and the outer edge of the chamber 17 as hereto-

fore described provide a refrigerated cabinet of the type disclosed wherein great utility and practical refrigeration effects are achieved due directly thereto, the gasket serving to hold the top portions firmly in position making them difficult to remove or displace, closing the space between the normally irregular shaped chambers 17 and the top members 11 and 12 and at the same time causing the resilient gasket itself to be positively positioned on the chamber 17 so that no matter how large a beverage container may be introduced into the opening 21 thereof the gasket will remain in proper position and fulfill its several duties as well as providing a yielding support for the jug or bottle inverted and placed thereon.

Having thus described my invention, what I claim is:

In a cooler cabinet of the class described wherein a plurality of containers are positioned, a pair of top members having downwardly depending flanges formed adjacent the outermost edges thereof adapted to engage the innermost edges of the said cooler cabinet to prevent outward movement of the said top members with respect to the said cooler cabinet matching oppositely disposed openings formed in the said top members and adapted to surround and enclose the said chambers, and gaskets formed with downturned annular flanges positioned on each of the said chambers, the said downturned annular flanges being positioned between said chambers and the said top portions, and held in distorted form therebetween by the said top members.

MURRAY M. FIBUS.
